CARTON

Bertram E. Baker, Boston, Mass.

Application February 11, 1936, Serial No. 63,369

9 Claims. (Cl. 206—58)

This invention relates to cartons and more particularly to paper cartons adapted to receive and for dispensing sheet material, such as wax paper.

It is an object of the present invention to provide a carton which can be manufactured at low cost.

It is another object of the invention to provide a carton which can be formed from a single blank, the various portions of which can be folded and self-interlocked in their carton forming positions.

Another object of the invention is the provision of a carton of the above general character which is adapted for dispensing sheet material, such as wax paper.

15 The invention will be more clearly understood from the following description in conjunction with the accompanying drawings, in which,

Fig. 1 is a plan view of a blank adapted to be folded to form a carton embodying the invention; Fig. 2 is a perspective view of a strip of hard pressed cardboard adapted to be assembled with the carton of the invention to adapt the same for use as a dispensing package for sheet material, such as wax paper;

25 Fig. 3 is a perspective view showing portions of the blank folded and positioned in their carton forming positions;

Fig. 4 is a perspective view showing other portions of the blank folded and positioned in their 30 carton forming positions;

Fig. 5 is a perspective view of the completed carton with the cover raised;

Fig. 6 is a perspective view of the completed carton with the cover closed and having housed 35 therewithin a roll of sheet paper, such as wax paper; and

Fig. 7 is a sectional elevational view of the carton as shown in Fig. 6.

Before explaining in detail the present invention it is to be understood that the invention is not limited in its application to the details of construction and arrangement of parts illustrated in the accompanying drawings, since the invention is capable of other embodiments and of being practiced or carried out in various ways.

45 Also it is to be understood that the phraseology or terminology employed herein is for the purpose of description and not of limitation, and it is not intended to limit the invention claimed herein beyond the requirements of the prior art.

A carton embodying the invention may be formed from a blank B of the general shape shown in Fig. 1. The blank B is scored along the parallel pairs of lines 1—1, 2—2, 3—3, 4—4, 10—10, 55 and 11—11 and is also scored along the lines 5—5,

6, 7, 8, 9 and 12—12. The blank B, is cut along the lines 15—15, 16—16, 17—17 and 18—18. The blank B scored and cut along the lines above indicated provides portions 20, 21, 22 and 23 adapted, when folded and positioned in carton forming position, to form the front wall, bottom wall, back wall and the top portion of the cover respectively. The portion 23 is provided with a projection 24 adapted to form the front wall of the cover and is itself provided at each end with 10 extensions 25 adapted to form the side portions of the cover. The extensions 25 each carry a flap 26 having slots 27 and 27a. The portion 20 is provided with a projection 28 at each end adapted to form the side or end walls of the carton. Each of the projections 28 are themselves provided with extensions 29 carrying tongues 30. The portion 22 is provided at each end with a flap 31 adapted to be folded against the outer surface of the side or end walls formed by the portions 28. The portion 21 is provided at each end with a projection 32 having an extension 33. The projections 32 are adapted to be folded against the outer surface of the flaps 31 and the projections 33 are adapted to be folded and positioned against the inner surface of the side walls formed by the portions 28.

To form the carton the blank B is first folded along the lines 8, 9, 1—1, and 11—11 and the portions 20, 21, 22, 28 and 29 brought to the 30 positions indicated in Fig. 3. It will be noted that when these portions are brought to the positions indicated in Fig. 3, the portions 20, 21, 22 and 28—28 form the front wall, bottom, back wall and the side or end walls of the carton respectively and the portions 29—29 are positioned against the inner surface of the back wall. The blank is now folded along the lines 6, 4—4, 5—5 and 7 and the portions 23, 24, 25—25 and 26—26 brought to the positions indicated in Fig. 4. 40 Thus, it will be noted that the portions 23, 24 and 25—25 form the top portion of the cover, the depending front of the cover and the depending sides of the cover respectively and the portions 26—26 are brought to positions adjacent the inner surface of the top portion 23 of the cover. The blank is now folded along the lines 12—12 and the tongues 30 inserted through the slots 27 of the flaps 26 as indicated in Figs. 4 and 5. The blank is now folded along the lines 3—3 to bring 50 the flaps 31 in engagement with the outer surface of the side or end wall portions 28, and the blank is then folded along the lines 2—2 and 10—10 to bring the projections 32—32 against the outer surface of the flaps 31 and to bring the 55

extensions 33 into engagement with the inner surfaces of the end wall portions 28 as indicated in Fig. 5.

If the carton is to be employed as a dispensing package for sheet material, such as wax paper, the angle shaped strip 35, which preferably is hard pressed cardboard or other thin stiff material, is assembled with the cover portion of the carton by bringing the portion 36 of the strip 35 between the top portion 23 of the cover and the flaps 26 and with the portion 37 of the strip 35 in engagement with the inner surface of the front depending portion 24 of the cover, the tongues 30 projecting between the portion 36 of the strip 15 and the top portion 23 of the cover of the carton. If desired, the portion 36 of the strip 35 may be provided with tabs 40 adapted to be inserted through the slots 27a. It will be noted that when the strip 35 is thus assembled with the cover the portion 37 thereof depends slightly below the lower edge of the depending front portion 24 of the cover as indicated in Figs. 4, 5 and 6. Thus, when a roll 38 of sheet material, such as wax paper, is positioned within the carton so as to extend over the top of the front wall 20 and downwardly between the front wall 20 and the strip 35, the lower edge of the portion 37 of the strip 35 serves as a cutting edge for cutting off a desired length of the sheet material.

It will be noted that when the various portions of the blank B are folded into their carton forming positions the parts reinforce and interlock with one another without necessitating the use of staples or glue to secure the parts together. Thus, the portions 29-29 are positioned in contact with the back wall 22 and the tongues 30 are interlocked with the flaps 26-26 by passing through the slots 27 therein. In this way the depending side walls 25-25 and the depending front portion 40 of the cover and the back wall 22, front wall 20 and the side or end walls 28-28 are held securely in their respective positions. The projections 32 are held in engagement with the flaps 31 by either the depending side walls 25-25 of the cover, when the cover is closed, or by engagement of the ends of the roll 38 of the sheet material with the extensions 33-33. Furthermore, the cutting strip 35 of hard pressed cardboard is held in desired position by the flaps 26-26. The insertion of the tongues 30-30 between the portion 36 of the strip 35 and the portion 23 of the cover prevents displacement of the flaps 26-26 and the depending front portion 24 and side portions 25-25 of the cover of the carton.

I claim:

- 55 1. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions, at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions.
- 60 2. A carton having an open top closed by a cover and formed from a one-piece blank having portions adapted to form the bottom and front and back walls and the top of the cover of the carton, said top portion having a front projection adapted to depend over said front wall, said front
- 65 3. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, and a separate detachable cutting strip having a portion extending between said slotted
- 70 4. A carton having an open top closed by a cover and formed from a one-piece blank having portions adapted to form the bottom and front and back walls and the top of the cover of the carton, said top portion having a front projection adapted to depend over said front wall, said front projection having extensions at each end adapted to provide depending side cover portions, said depending side cover portions each carrying a slotted flap adapted to be folded into a position adjacent the inner surface of the top of the cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions.
- 75 5. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, said back wall portion having flaps adapted to overlap said carton side walls, said bottom portion having projections at each end adapted to be folded to embrace said last mentioned flaps and the inner surfaces of said carton side walls.
- 80 6. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, said back wall portion having flaps adapted to overlap said carton side walls, said bottom portion having projections at each end adapted to be folded to embrace said last mentioned flaps and the inner surfaces of said carton side walls.
- 85 7. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, and a separate detachable cutting strip having a portion extending between said slotted

projection having extensions at each end adapted to provide depending side cover portions, said depending side cover portions each carrying a slotted flap adapted to be folded into a position adjacent the inner surface of the top of the cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions.

8. A carton having an open top closed by a cover and formed from a one-piece blank having portions adapted to form the bottom and front and back walls and the cover of the carton, said cover portion carrying at each end a slotted flap adapted to be folded into position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, said back wall portion having flaps adapted to overlap said carton side walls, said bottom portion having projections at each end adapted to be folded to embrace said last mentioned flaps and the inner surfaces of said carton side walls.

9. A carton having an open top closed by a cover and formed from a one-piece blank having portions adapted to form the bottom and front and back walls and the top of the cover of the carton, said top portion having a front projection adapted to depend over said front wall, said front projection having extensions at each end adapted to provide depending side cover portions, said depending side cover portions each carrying a slotted flap adapted to be folded into a position adjacent the inner surface of the top of the cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, said back wall portion having flaps adapted to overlap said carton side walls, said bottom portion having projections at each end adapted to be folded to embrace said last mentioned flaps and the inner surfaces of said carton side walls.

10. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their carton forming positions, and a separate detachable cutting strip having a portion extending between said slotted

flaps and said cover and another portion depending over the carton front wall.

6. A carton having an open top closed by a cover and formed from a one-piece blank having portions adapted to form the bottom and front and back walls and the top of the cover of the carton, said top portion having a front projection adapted to depend over said front wall, said front projection having extensions at each end adapted to provide depending side cover portions, said depending side cover portions each carrying a slotted flap adapted to be folded into a position adjacent the inner surface of the top of the cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their folded carton forming positions, and a separate detachable cutting strip having a portion extending between said slotted flaps and said cover and another portion depending over the carton front wall.

7. A carton having an open top closed by a cover and formed from a one-piece blank having portions adapted to form the bottom and front and back walls and the cover of the carton, said cover portion carrying at each end a slotted flap adapted to be folded into a position adjacent the inner surface of the top of said cover, said front wall portion having extensions at each end adapted to form the carton side walls, said carton side walls each having an extension adapted to be folded into position adjacent said back wall, said carton side wall extensions having tongues adapted to be inserted in the slots of said flaps to secure the portions of said blank in their

carton forming positions, and a separate detachable cutting strip having a portion extending between said slotted flaps and said cover and another portion depending over the carton front wall, said tongues extending between said strip and said cover.

8. A carton having an open top closed by a cover and formed from a one piece blank having portions adapted to form the bottom and front and back walls and the cover of a carton, said cover portion carrying at each end a flap adapted to be folded into a position adjacent the inner surface of the top of said cover, said front wall portion having extensions at each end adapted to form the carton side walls, means for holding said side walls and said flaps in their completed carton positions, and a separate detachable cutting strip having a portion extending between said flaps and said cover and another portion depending over the carton front wall.

9. A carton having an open top closed by a cover and formed from a one piece blank having portions adapted to form the bottom and front and back walls and the cover of a carton, said cover portion carrying at each end a flap adapted to be folded into a position adjacent the inner surface of the top of said cover, said front wall portion having extensions at each end adapted to form the carton side walls, means for holding said side walls and said flaps in their completed carton positions, and a separate detachable cutting strip having a portion extending between said flaps and said cover and another portion depending over the carton front wall, said flaps each having a slot adapted to receive a portion of said cutting strip.
